UNITED STATES PATENT OFFICE

2,406,062

METHOD FOR MAKING DISHED DISK WHEELS

Dana R. Cornell, East Chicago, Ind., assignor to
 Standard forgings Corporation, Chicago, Ill., a
 corporation of Delaware

Application August 24, 1944, Serial No. 550,959

1 Claim. (Cl. 29—159.01)

1

This invention relates to a method for making dished disk wheels, and particularly for making disk wheels which are deeply dished.

The disk wheels to be produced by my method are tapered in thickness, radially, from an annular region outwardly of the hub portion to the peripheral edge of the disk, and are provided with a plurality of hand holes located in the web portion between said hub portion and the peripheral edge. The disk, as initially forged, is relatively flat and is subjected to severe bending and forming operations in order to produce the deeply dished disk wheels of my invention.

By using the method hereinafter described, several important advantages are attained. The forged, relatively flat disk while still hot, is subjected to trimming and preforming in one operation, punching of the central aperture and hand holes in another operation, and final forming in a third operation. By this method, the hand holes can be punched through the web of the disk after it has been moderately bent and formed but while it is still fairly flat, and sufficient backing is afforded by a lower, supporting die to properly support the disk while it is being punched. However, the major bends are placed in the disk in the first forming operation, prior to the punching, so that the final forming operation does not distort unduly the metal around the hand holes, thus minimizing distortion in a part of the disk which is particularly subject to load strains in operation. Although the disk is deeply dished in the final forming operation, the major bends placed therein in the first forming operation are not greatly affected in said final forming step and this is a desirable feature of my invention for the reason that the major bends should be accomplished while the disk is still solid.

Punching of the hand holes between the first and final forming operations results in cut edge surfaces which are substantially at right angles to the adjacent surfaces of the disk instead of forming acute angles as would be the case were the hand holes punched after the final forming. My method permits of the use of multiple punching, whereas, if it were attempted after the final forming of the deeply dished disk, to produce hand holes of the form herein shown, index punching would have to be resorted to. By index punching is meant a method wherein the work is turned intermittently and each hand hole is formed separately by a punching tool mounted at an inclined angle in order to work on the dished surface to be punched. Multiple punch-

2

ing, obviously, is much more economical, and, furthermore, the hand holes produced thereby are uniform in size and spacing, a result difficult to attain by index punching.

Flexing of the finished wheel takes place to a maximum degree in the rim portion which has the largest circumference and least thickness. Therefore, it is of particular importance to avoid weakening the rim region of the disk by cutting off metal on acute angles to form the necessary hand holes. Excessive metal is cut away when the hand holes are punched out after the final shaping of the deeply dished disk and therefore my method of punching the holes between the first and final forming operations serves several purposes: conserving the metal around the hand holes; preserving the right angle relationship of the cut edges and adjacent disk surfaces; minimizing the length of the stroke of the press required for punching the holes before the disk has been given its deep dished form; facilitating the punching by accomplishing it before the disk has become cool; and avoiding distortion of the metal which would result if the major bends were formed in the disk after the punching operation.

In the drawings:

Fig. 1 is a vertical sectional view of a pair of dies for preforming and trimming the relatively flat forged disk.

Fig. 2 shows the apparatus of Fig. 1 in another position and shows the forged disk trimmed and preformed.

Fig. 3 is a vertical sectional view of punching apparatus, showing the preformed disk after the central aperture and hand holes have been cut.

Fig. 4 is a vertical sectional view on an enlarged scale of a part of a pair of dies for finally forming the punched, preformed disk.

Fig. 5 is a plan view of the finished disk.

Fig. 6 is a transverse section, on an enlarged scale, taken in the plane of the line 6—6 of Fig. 5, looking in the direction indicated by the arrows.

In the preferred embodiment of the invention shown in the drawings, the forged steel disk, as shown in Fig. 1, is substantially flat and smooth on its surface 10 and provided with a central boss 11. The opposite surface has a central boss 12, a surrounding flat annular portion 13, thickened annular portion 14, radially inclined region 15 and peripheral flat, narrow fin surface 16.

The apparatus for trimming and preforming the forged disk, shown in Figs. 1 and 2, comprises dies 17 and 18. The die 17 is mounted in a suitable reciprocating support (not shown)

and its face is complementary to the intended surface of one side of the disk in its preformed stage. Said die has a central recess 19, a flat annular surface 20, a radially curved concentric ring 21, two radially downwardly inclined concentric surfaces 22 and 23 and a peripheral horizontally disposed surface 24. On the outer edge of the surface 24 is a peripheral cutting edge 25 made of stellite, chromium or other suitable material welded on the carbon steel casting constituting the die 17.

The lower forming die 18 is rigidly mounted on an anvil 26 having a flat shoulder 27 on which is mounted, by a bolt 28, a circular housing 29 internally recessed at 30, to accommodate a ring 31 between the housing 29 and the die 18. The ring 31 is supported on a plurality of coiled springs 32, located beneath the flanges of the ring adapted to move vertically in the recesses 30 of the housing 29. The ring 31 has a flat upper surface.

The face of the die 18 is provided with a central recess 34, surrounded by a flat annular surface 35, radially curved concentric ring 36 and radially downwardly inclined portions 37 and 38.

The forged disk is placed on the lower forming die 18 with its flat surface 10 adjacent the face of the die, and the central boss 11 in the recess 34. In this position the disk surfaces 13, 14, 15 and 16 face the upper die 17 as shown in Fig. 1 and the peripheral portion of the disk is engaged between the flat peripheral surface 24 and the top of the ring 31. As the die 17 is moved downwardly, the engaging members 24 and 31 continue to clutch the disk and prevent wrinkling of the metal as the diameter and circumference of the disk are reduced in the preforming operation. As the cutter edge 25 meets a cutter edge 33 fixed on the inner edge of the housing 29, the disk is peripherally trimmed by cutting off the fin 16, and as the die 17 continues its downward movement, the ring 31 is depressed, the disk gradually slips from between the holding surfaces and the parts assume the position shown in Fig. 2.

In Fig. 2 is shown the preformed, trimmed, moderately dished disk as it appears in section after the first forming operation. In this form, the upper surface comprises the central boss 34, flat annular hub portion 35, downwardly curved annular ring 36 in which is utilized the metal of the thickened portion 14 (Fig. 1), flat radially downwardly inclined annular portion 37, downwardly curved annular ring 38 and circumferential rim portion 39. The lower surface of the preformed disk comprises the boss 40, and surfaces 41, 42, 43 and 44, which together with the upper surfaces described form a disk of substantially uniform thickness in the central hub portion including the inner major bend, and of gradually decreasing thickness in the region between said major bend and the peripheral edge 45.

While the preformed disk is still relatively flat in the region defined by the surfaces 37-43, between the bends 36 and 38, it is subjected to a multiple punching operation in which the central bosses 34 and 40 and part of the surrounding portions 35-41 are cut out to form a hub center, and hand holes are cut through the web portion 37-43. I have shown eight hand holes but the number may vary, usually between five and ten. In Fig. 3, I have shown punching apparatus for multiple punching, that is, for providing the central opening and the desired number of hand holes in one punching operation. The upper punching die 46 has cutters 47 for cutting the

hand holes, and a cutter 48 for cutting the central opening. It also is provided with a disk bearing member 49, spring pressed by the springs 50. Another disk bearing member 51, preferably integral with the member 49 and also held down by the action of the springs 50 bearing on the part 49, bears on the peripheral portion of the disk while the cutting takes place. The lower die 52 has an annular groove or opening 53 through which the cut out metal to form the holes 54 may pass, and it has a central compressible member 55 supported by a spring 56 for cooperating with the cutter 48. The peripheral disk supporting member 57 cooperates with the upper die member 51 to hold the rim portion of the disk during the punching operation.

Because of the fact that the web region 37-43 (Fig. 2) of the disk is relatively flat when the hand holes are punched (Fig. 3), the stroke of the cutters 47 and 48 may be relatively short. Also, although the cutters move in vertical planes, the cut edges of the disk are substantially at right angles to the adjacent disk surfaces at the end of the punching operation shown in Fig. 3, thereby avoiding the formation of acute angles in the finished disk.

The next and final step of my process is shown in Fig. 4, where the preformed, trimmed and punched out disk is subjected to its final forming operation by upper and lower dies 58, 59 respectively. These dies have disk bearing surfaces complementary to the finished form of the deeply dished disk shown in section in Figs. 4 and 6, and in plan view in Fig. 5. In its finished form, said disk retains the preformed surfaces 35, 41, 36 and 42, with the central portion cut away to form the opening 60, but radially outwardly of said preformed major bend 36-42, the web region 37-43 of the punched out disk is given another annularly located, radially extending bend 61 which shapes the metal between and surrounding the hand holes 54 and changes the angular position of the rim portion 38, 39, 44 (Figs. 2 and 3) to the position indicated at 62, 63, 64 and 65 in Figs. 4, 5 and 6.

As best shown in Fig. 6, these operations result in forming a deeply dished disk with hand holes having cut edges 66 and 67 substantially at right angles to the adjacent surfaces of the rim region of the disk. It is essential to preserve this relationship of the metal surfaces particularly in the rim region of the disk which is relatively thin and subjected to the greatest flexing and strain in use. By my apparatus and method I avoid cutting away of metal and the forming of acute angles between the hand hole edges and adjacent surfaces, in addition to the advantage of using multiple punching as heretofore mentioned.

It will be understood from the foregoing that my method comprises the preforming and trimming of a disk initially forged relatively flat, to provide two annular major bends such as defined by the curved surfaces 36-42 and 38-44, with a relatively flat web portion between them, then subjecting the preformed disk to a multiple punching operation which cuts a central opening in the disk and a plurality of hand holes in the web portion between said major bends, and finally subjecting the preformed, trimmed and punched out disk to another forming operation in which an annular bend is made in the web portion as indicated at 61 in Fig. 5, between the preformed major bends, whereby the angular disposition of the rim portion of the disk is al-

tered, and the disk as a whole is deeply dished, all without undue distortion of the metal, while retaining required strength and contour where needed in the finished disk.

Changes may be made in details of construction of the apparatus described without departing from my invention as set forth by the following claim.

I claim:

The method of making a deeply dished disk wheel having a relatively flat hub center and axially dished web portions terminating in a cylindrical rim portion, which comprises the step of preforming a relatively flat forged steel disk with an annular hub portion of substantially uniform thickness surrounded by an annular rim portion and a relatively thickened annular portion between the hub and rim portions, yieldably clamping the periphery of the rim portion while initially bending the disk axially at said thickened

portion and utilizing the metal of said portion to make the thickness of the bend substantially conform with that of the hub portion, and also bending the peripheral rim portion as it gradually slips from between the clamping means preventing wrinkling of the metal as the diameter and circumference of the disk are reduced, thus providing the disk with two axially curved concentric major bends connected by a frusto-conical web portion in the initial bending operation, simultaneously punching a central aperture in the hub center portion and a plurality of hand holes in the web portion, and finally bending and axially curving the web portion while maintaining the concentric bends substantially as formed, whereby the disk is deeply dished and the periphery of the rim portion is disposed substantially at right angles to the hub portion.

DANA R. CORNELL.
